E. B. LINDSEY.
WIRE STRETCHER.
APPLICATION FILED AUG. 5, 1916.

1,204,168.

Patented Nov. 7, 1916.

By Watson E. Coleman

Attorney

UNITED STATES PATENT OFFICE.

EDDIE B. LINDSEY, OF BUFFALO, ALABAMA.

WIRE-STRETCHER.

1,204,168.

Specification of Letters Patent. Patented Nov. 7, 1916.

Application filed August 5, 1916. Serial No. 113,299.

To all whom it may concern:

Be it known that I, EDDIE B. LINDSEY, a citizen of the United States, residing at Buffalo, in the county of Chambers and State of Alabama, have invented certain new and useful Improvements in Wire-Stretchers, of which the following is a specification, reference being had to the accompanying drawings.

10 This invention relates to certain improvements in wire stretchers and it is an object of the invention to provide a device of this general character having novel and improved means whereby the same may be employed with equal facility for a multiplicity of purposes such as a jack and as a vise.

15 The invention also has for an object to provide a novel and improved device of this general character including a screw bar provided with means for rotating the same together with two coacting jaws, one of said jaws having a substantially fixed position longitudinally of the bar while the second jaw is capable of movement longitudinally 25 of the bar upon rotation thereof.

20 A still further object of the invention is to provide a novel and improved device of this general character wherein two relatively movable jaws are employed and 25 wherein each of said jaws is provided with means whereby a wire or the like may be clamped thereto.

30 The invention consists in the details of construction and in the combination and arrangement of the several parts of my improved wire stretcher whereby certain important advantages are attained and the device is rendered simpler, less expensive and otherwise more convenient and advantageous 40 for use, all as will be hereinafter more fully set forth.

The novel features of the invention will hereinafter be definitely claimed.

In order that my invention may be the 45 better understood, I will now proceed to describe the same with reference to the accompanying drawings, wherein—

Figure 1 is a view in top plan illustrating a wire stretcher constructed in accordance 50 with an embodiment of my invention, a co-acting post being indicated in section; Fig. 2 is an enlarged sectional view taken substantially on the line 2—2 of Fig. 1; Fig. 3 is an enlarged sectional view taken substantially on the line 3—3 of Fig. 1; Fig. 4 is 55 an enlarged sectional view partly in section

and partly in elevation illustrating the base plate as herein embodied, the coacting screw bar being shown in section; and Fig. 5 is a sectional view taken substantially on the line 5—5 of Fig. 1, a coacting portion of the screw bar being shown in elevation.

As disclosed in the accompanying drawings, P denotes a plate preferably formed in two sections and connected one to the other through the medium of the bolts 1, and the adjacent margins of the sections are provided with the upstanding flanges 2 which, when the sections are in assembled relation, afford a socket 3 for the reception 70 of an end portion of the bar 4.

The flanges 2 are provided with the inwardly directed beads or ribs 5 adapted to be received within an annular groove 6 produced within the bar 4 whereby it will be 75 perceived that the bar 4 has swiveled connection with the plate P. It is also preferred that the flanges 2 be provided with the registering perforate ears 7 through which additional clamping bolts 8 are disposed. The opposite end portion of the bar 4 is enlarged, as at 9, and is loosely disposed through the sleeve 10 of the jaw A. Fixed to the bar 4 inwardly of the sleeve 10 and contacting therewith is the sleeve 11 where- 85 by it will be perceived that the sleeve 10 and its jaw A are held against movement longitudinally of the bar 4 but are capable of movement therearound.

Suitably affixed to the bar 4 adjacent the 90 plate P is a ratchet operating member R whereby the requisite rotation may be imparted to the bar 4. The operating member R may be of any construction which will best meet the requirements of practice and 95 as the specific construction thereof forms no part of my present invention, it is thought that a detail description and illustration thereof is unnecessary.

The periphery of the bar 4 intermediate 100 the operating member R and the sleeve 10 is threaded and said threaded portion is disposed through and operatively engaged with the second jaw B, one end portion of which being extended, as at 12, and adapted to contact with a fence post or the like when the device is employed as a wire stretcher. When used as a wire stretcher it is to be understood that the bar 4 is horizontally disposed and if used solely for the purpose of 105 stretching a wire, the wire to be stretched is secured, in a manner which will hereinafter 110

be more fully set forth, to the jaw A. It will be perceived that upon requisite rotation of the bar 4 the same will move longitudinally through the jaw B and thereby stretch 5 the wire. When the device is to be used for connecting the ends of adjacent wires, the end portions of said wires will be secured to both of the jaws A and B in a manner and for a purpose which is believed to be clearly 10 apparent to those skilled in the art to which my invention appertains.

Corresponding faces of the jaws A and B, the upper faces when the bar 4 is in horizontal position, are provided with the longitudinally directed grooves or channels 14 in each of which is positioned a block 15 having its inner face serrated and provided with the overlying flange 16. Also positioned within the groove 14 is a second block 17 having its 15 inner face also serrated and which is adapted to coact with the block 15 to clamp a wire therebetween. This block 17 is adapted to pass beneath the flange 16 whereby it will be at once self-evident that the flange 16 serves 20 to hold the wire between the jaws especially during the clamping operation. Threaded through an end of the jaw is the operating screw 18 which coacts with the block 17 and serves as a medium whereby the wire may be 25 effectively maintained between the jaws 15 and 17. It is to be noted that the jaw B is also provided with a sleeve 19 and with which the bar 4 directly coacts. It is also to be noted that the opposed faces of the jaws 30 A and B at their corresponding free end portions are also serrated so that when required said jaws may be conveniently employed as a vise.

When it is desired to employ my improved 35 device as a jack the end portion of the jaw B opposite to the extension 12 is employed in a manner which is believed to be self-evident. It will also be appreciated that when the device is used as a jack the upper jaw 40 A may be readily swung into such a position as to afford no obstruction. I also find it of advantage to provide the jaw A with the extension 20 which serves as a handle or 45 hand grasp to facilitate the handling of the implement.

When the device is employed as a jack in connection with heavy work it has been found of particular advantage to secure the 50

plate P to a block of wood or the like and for this reason I provide the corner portions 55 of the plate P with the openings 21 through which suitable anchoring means are adapted to be disposed in order to securely affix the same to said block.

From the foregoing description, it is 60 thought to be obvious that a wire stretcher constructed in accordance with my invention is of an extremely simple and comparatively inexpensive nature and is particularly well adapted for use by reason of the convenience and facility with which it may be assembled, and it will also be obvious that my invention is susceptible of some change and modification without material departure from the principles and spirit thereof and for this reason I do not wish to be understood as limiting myself to the precise arrangement and formation of the several parts herein shown in carrying out my invention in practice, except as hereinafter claimed.

I claim:

1. A device of the character described comprising an elongated bar, a jaw rotatably engaged with the bar and held against movement longitudinally thereof, a second jaw capable of movement longitudinally of the bar, each of said jaws being provided in a side face with a groove, a pair of blocks positioned within said groove, and means for imparting movement to one of the blocks relative to the other.

2. A device of the character described comprising an elongated bar, a jaw rotatably engaged with the bar and held against movement longitudinally thereof, a second jaw capable of movement longitudinally of the bar, each of said jaws being provided in a side face with a groove, a pair of blocks positioned within said groove, and means for imparting movement to one of the blocks relative to the other, said movable block being provided with a flange extending in a direction toward the second block and adapted to overlie the same when said blocks are in close proximity one to the other.

In testimony whereof I hereunto affix my signature in the presence of two witnesses.

EDDIE B. LINDSEY.
